BALL WHIRLING TOY

Melvin L. Vincent, 17535 St. Aubin,
Detroit, Mich. 48215

Filed Apr. 26, 1971, Ser. No. 137,723

Term of patent 14 years

Int. Cl. D21—01

U.S. Cl. D34—15 K

FIG. 1

FIG. 5

FIG. 2

FIG. 3

FIG. 4

FIG. 1 is a front perspective view of a ball whirling toy showing my new design;

FIG. 2 is a front elevational view thereof;

FIG. 3 is a side elevational view;

FIG. 4 is a bottom plan view;

FIG. 5 is a cross section taken on line 5—5 of FIG. 2.
I claim:

The ornamental design for a ball whirling toy, substantially as shown.
